(57) **CLAIM**

The ornamental design for an imaging device with a display screen, as shown and described.

DESCRIPTION

FIG. 1 is a front perspective view of an imaging device with a display screen;

FIG. 2 is a top plan view thereof;

FIG. 3 is a bottom plan view thereof;

FIG. 4 is a rear elevation view thereof;

FIG. 5 is a front elevation view thereof;

FIG. 6 is a right side elevation view thereof;

FIG. 7 is a left side elevation view thereof; and,

FIG. 8 is a front perspective view thereof, showing an environmental image of a fragmentary human body in broken lines which forms no part of the claimed design.

The broken lines in FIGS. 1 and 2 are included for the purpose of illustrating environmental subject matter and form no part of the claimed design.
